TELEVISION CABINET

Randall Rasmussen, Orem, Utah, assignor of fifteen per cent to Louis Rasmussen, Orem, Utah

Application January 5, 1954, Serial No. 28,385

Term of patent 14 years

(Cl. D56—4)

To all whom it may concern:

Be it known that I, Randall Rasmussen, a citizen of the United States, residing at Orem, in the county of Utah and State of Utah, have invented a new, original, and ornamental Design for a Television Cabinet, of which the following is a specification, reference being had to the accompanying drawing, forming part thereof.

The single drawing figure is a perspective view of a television cabinet showing my new design.

I claim:

The ornamental design for a television cabinet, as shown.
